UNITED STATES PATENT OFFICE

JOHN Q. SHUNK, OF BUCYRUS, OHIO

STREET MARKER

Application filed December 12, 1929. Serial No. 413,560.

The invention relates to improvements in spiked-down disk markers used in forming lines for traffic guiding purposes, cross-walks, safety zones, parking areas, etc.

5 It is one object of the invention to provide a unique annular support for a concavo-convex marking disk, which will prevent partial or total flattening thereof under the weight of heavy trucks, wagons, etc., the 10 disk being thus prevented from loosening its engagement with its anchoring spike.

A further aim is the provision of a unique spike formed with novel anchoring means preventing it from creeping out of the pavement into which it is driven.

With the foregoing in view, the invention resides in the novel subject matter herein-after described and claimed, description being accomplished by reference to the accompanying drawings.

Fig. 1 is a top plan view of a marker and spike.

Fig. 2 is an edge view of the marker and a side elevation of its anchoring spike.

25 Fig. 3 is a vertical sectional view on line 3—3 of Fig. 2, the spike being shown in elevation.

Fig. 4 is a top plan view of the annular disk support.

30 Fig. 5 is a vertical sectional view on line 5—5 of Fig. 4.

Fig. 6 is a horizontal sectional view through the spike, as indicated by line 6—6 of Fig. 3.

35 In the drawing above briefly described, the numeral 7 denotes a concavo-convex marking disk having a central depressed portion 8 and a central opening 9 in said depressed portion. Disposed under the disk

40 7 is an annular support 10 which contacts with the lower side of said disk and is provided with a flat lower side to rest upon the surface of the street S, upon which the marker is used. The inner diameter of

45 the support 10 is such as to snugly receive the depressed disk portion 8 as seen in Fig. 3, thereby relatively centering the disk and the support.

The support 10 preferably comprises a flat annular base portion 11 and inner and

outer concentric flanges 12—13 integral with and projecting upwardly from said base portion, the flange 12 being of greater height than flange 13 and engaging the depressed disk portion 8. Both the support 55 10 and the disk 7 may either be formed by pressing the metal into shape or by casting it.

A unique anchoring spike 14 is provided, said spike having a head 15 at its upper end, a pointed lower end 16, an enlargement 17 between its ends for anchoring purposes, and a cylindrical enlargement 18 directly under the head 15 and integral with the latter, the lower end 19 of said enlargement 18 60 being downwardly tapered to the smallest diameter of the spike.

In forming the anchorage enlargement 17, diametrically opposed sides of the spike 14 are pressed inwardly as shown at 20, thus 65 causing bulging of the spike in a direction at right angles to the line of pressure, to form said enlargement. This enlargement 17 is of a maximum diameter to pass freely through the opening 9 of the disk 7, and when the spike is driven into the street S, said enlargement displaces some of the paving material which latter creeps back and snugly surrounds the spike, tightly embedding the latter. The enlargement 18 is of 70 a size to completely fill the opening 9 and hence radial shifting of the disk 7 upon the driven spike is prevented. Were it not for this enlargement 18, only a loose connection 75 could be provided between the spike and disk for the opening 9 is necessarily of greater diameter than the smaller diameter of the spike 14, in order to permit passage of the anchoring enlargement 17 through said opening, but by the provision of said 80 enlargement 18, a tight connection between spike and disk is insured.

It will be seen from the foregoing that a novel and advantageous construction has been provided in which danger of distorting 85 the disk under the weight of heavy loads is prevented, and in which the anchoring spike is held against creeping from the pavement into which it is driven. The details disclosed for obtaining these results, are 90 95 100

preferably followed, but within the scope of the invention as claimed, variations may be made.

I claim:—

- 5 1. A street marker comprising a concavo-convex disk having a depressed central portion and a central spike-receiving opening in said portion, and an annular support under said disk of considerably less diameter than the latter, said support comprising a flat base portion for contact with the street, and inner and outer concentric flanges rising from said base portion and contacting with the lower side of the disk, said inner flange surrounding said depressed disk portion to relatively center the disk and support, said disk being sufficiently stiff to prevent depression between its supported portions under the weight of heavy vehicles.
- 10 2. In a street marker, an annular support for a concavo-convex marking disk, said support comprising a flat base portion of considerably less diameter than the disk with which it is to be used and inner and outer concentric flanges integral with and rising from said base portion.
- 15 3. In a street marker, an annular support for a concavo-convex marking disk, said support comprising a flat base portion of considerably less diameter than the disk with which it is to be used and inner and outer concentric flanges integral with and rising from said base portion, the inner flange being of greater height than the outer flange.

In testimony whereof I have hereunto affixed my signature.

JOHN Q. SHUNK.
